PRESSURE INDICATOR

Robert G. Miner, Jr., Toledo, Ohio, assignor, by
mesne assignments, to Moto Meter Gauge &
Equipment Corporation, a corporation of Dela-
ware (1935)

Application November 21, 1931, Serial No. 576,566

10 Claims. (Cl. 177—311)

This invention relates to pressure indicators and more particularly to pressure indicators which give an indication when a predetermined or critical pressure is reached and it is an object of this invention to provide an improved pressure indicator which will be operated to give an indication when a predetermined pressure is reached. It is also an object of this invention to provide a pressure indicator having pressure responsive means subjected to the pressure whose condition is to be indicated and operated to cause an indication to be given when the pressure to which it is subjected falls to a predetermined pressure.

In the drawings—

15 Fig. 1 is a diagrammatic view of an apparatus for using gas under pressure with a pressure indicator constructed in accordance with this invention applied thereto;

20 Fig. 2 is a view partly in section and partly in elevation of the pressure indicator shown in Fig. 1;

Fig. 3 is a view in section of part of the pressure indicator shown in Fig. 2;

Fig. 4 is a vertical section taken on the line 4—4 of Fig. 3;

25 Fig. 5 is a view in section of another part of the pressure indicator shown in Fig. 2; and

Fig. 6 is a vertical section taken on the line 6—6 of Fig. 5.

In the drawings an apparatus constructed in accordance with this invention is shown applied to an apparatus using the gas from containers containing gas under pressure. As shown, gas storage containers 1 and 1' having outlet valves 2 and 2' are joined by pipes 3 and 3' to a header 4, valves 5 and 5' being provided for cutting off the connection of either container from the header. From the header the gas passes through a reducing valve 6 and a pipe line 7 to the means in which it is used, such a means being shown in Fig. 1 as a gas stove 8. For purposes of this kind, tanks 1 and 1' are furnished containing gas under considerable pressure and one container, at a time, is connected to the header 4 and the gas supplied by pipe line 7 to the point of consumption. As the gas is used, the pressure in the connected container as container 1 falls and in order to notify the consumer that it is necessary to connect a fresh tank to the header as the gas in the tank connected is becoming exhausted, there is provided an indicating mechanism comprising a pressure unit 10 connected through pipe 12 to the header 4 and through a pipe 14 to an indicating means 16 which is placed where it is observed by the person using the gas supply.

55 The pressure unit 10 comprises a lower casting

18 and an upper casting 20, the lower casting having a threaded opening 22 by which the casting is attached to the pipe 12 and an annular flange 24 which forms a seat for a diaphragm 26 and is perforated to receive the bolts 28 by means of which the upper casting 20 is secured to the lower casting 18, the upper casting 20 and the bolts 28 serving to retain the diaphragm 26 on its seat. The upper casting 20 comprises a substantially flat or plate portion 21 having a substantially inverted U-shaped housing 30 formed integral therewith. To the upper portion of the housing 30 are secured extensions 32 having outwardly projecting flanges 34 provided with openings and adapted to serve as an attaching bracket 15 for the pressure unit 10 when desired. In the upper portion of the housing 30 is a threaded opening in which is adjustably secured a sleeve 36 having a rod or plunger 38 slidably mounted therein. To the lower end of the plunger 38 is secured an inverted substantially U-shaped yoke 40 which, at its lower end, is pivotally connected to a rod 42 which projects through an opening in the plate portion 21 of the upper casting 20 and is provided with a circular head 44 which bears upon the diaphragm 26. One side of the housing 30 is provided with a threaded opening in which is mounted a hollow bushing 46 which serves to secure a cylinder 48 to the housing 30 and as a guide for the rod 50 which is connected, at one end, to a piston 52 in the cylinder 48 and extends through the bushing 46 and through an opening in the opposite side of the housing 30. The rod 50 is provided at its other end with an operating knob or handle 54. Between the piston 52 and the outer end of the cylinder 48 is placed a spring 56 which tends to return piston 52 to the end of the cylinder 48 adjacent the housing 30.

Intermediate its length the rod 50 is formed with a notch 58 which is engaged by a latch 60 formed as a yoke pivoted at 62 to the housing 30 and having a portion 60' adapted to engage in the notch 58. The side portions of the latch 60 pass outside of the yoke 40 and are positioned to be engaged by projections 40' on the side portions of the yoke 40 when the yoke 40 is moved downwardly by a spring 64 which surrounds the plunger 38 and is compressed between the upper portion of the yoke 40 and the inner end of the sleeve 36. To ensure engagement of the latch 60 in the notch 58 when the latch is not pressed downwardly by the yoke 40 there is provided a spring 66 confined between the portion 60' of the latch 60 and the flat portion 21 of the upper casting 20. Detachable sides 57 are secured to the hous-

ing 30 by bolts 59 to complete the enclosing of the apparatus.

Extending from the cylinder 48 is a tube 14 of extremely small bore so that the volume thereof will be relatively small compared to the volume of the cylinder 48. The tube 14 extends to an indicating means 16 comprising a base plate 70 to which is secured a cylinder 12 connected to the tube 14 and having a piston 74 loosely fitted therein. The piston 74 is connected through connecting rod 76 to one end of counter-weighted arm 78 pivotally mounted on pin 80 supported by the base plate 70. Projecting from the arm 78 is a weighted angularly disposed arm 82 which engages with the stops 83 and 83' to limit the movement of the arm 78 and the arm 78 is also provided with a projection 84 which is concentric with the pivotal axis of the arm 78 and carries an indicating dial 86. To the baseplate 70 is secured an annular side wall 88 to which is attached a perforated front plate 90 and a glass cover 92.

If it is desired to give an additional indication at some point remote from the indicating means 16 there may be provided an audible indicating means as a bell 94 operated by current supplied from a battery 96 or other suitable source of current through a circuit comprising leads 97 and 98 which extend to contacts 99 and 100 carried by the baseplate 70. As shown in Figure 6, contact 100 is provided with an extension adapted in one position of the arm 78 to be engaged by insulated pin 82' mounted on the arm 82 to cause the contacts 99 and 100 to engage, completing the circuit for the bell 94. An additional audible indication may be given as by bell 91 supplied with current from a suitable source of current, as battery 93, by a circuit comprising leads 101 and 102 which extend to contacts 103 and 104 carried by the housing 30. Contact 103 is extended so as to be engaged by insulated pin 106 carried by the yoke 40 and positioned to separate the contacts 103 and 104 when the yoke 40 is in its upper position.

With the pressure unit 10 connected to the header 4, and gas being supplied thereto from one of the tanks the pressure in the header 4, passing through pipe 12 and acting upon the diaphragm 26 is normally sufficient to overcome the resistance of the spring 64 and raise the plunger 42, yoke 40 and plunger 38 to their uppermost position as shown in Figure 3. With the yoke 40 raised, movement of the rod 50 by handle 54 to the left as shown in Figure 3, will permit the spring 66 to raise the latch 60 so that the part 60' thereof engages in the notch 58 in the rod 50, thus retaining the piston 52 in the position shown in Figure 3 with the spring 56 under compression. When thus raised the yoke 40 through the engagement of the pin 106 with the contact 103, raises the contact 103 and interrupts the circuit between the contacts 103 and 104 and prevents any signal being given by means of the bell 91. Movement of the rod 50 and piston 52 to the left in Figure 3 causes pressure to be generated in cylinder 48 and tube 14 which acts upon the piston 74, raising piston 74 and shifting arm 78 and arm 82 to the dotted line position shown in Figure 6 and rotating the dial 86 therewith so that the dial 86 gives an indication that the pressure in the header 4 is above that at which the pressure unit 10 operates. Movement of the arm 78 and the arm 82 carries the pin 82' away from the contact 100, permitting the contacts 99 and 100 to separate and open the circuit of the bell 94, thus preventing any indication being given by

the bell 94 while the pressure in the header 4 is above the pressure at which the pressure unit 10 operates.

As the gas in the tank connected to the header 4 is consumed, the pressure in the tank falls until 5 eventually a pressure is reached at which the spring 64 overcomes the pressure acting upon diaphragm 26 and through yoke 40 and plunger 42 forces diaphragm 26 downwardly. The yoke 40, through its projections 40', operates the yoke 10 60 and disengages the portion 60' thereof from the notch 58 of the rod 50 permitting the spring 56 to force the piston 52 to the other end of the cylinder 48. The movement of the piston 52 reduces the pressure in the pipe 14 and causes a 15 difference of pressure at opposite sides of the piston 74 which operates the piston 74, moving the arm 78 to the position shown in full lines in Figure 6 and shifting the dial 86 to give an indication that the pressure in the tank has fallen to 20 the point at which it is desirable to substitute another tank. The pressure at which spring 64 operates the diaphragm 26 is determined by the adjustment of the sleeve 36.

When an audible indication is connected with 25 the indicating unit 16, the movement of the arm 78 and arm 82 causes the pin 82' to engage the contact 100, moving contact 100 to engage with contact 99 and complete the circuit of the bell 94 30 to give an audible indication of the pressure in the tank.

Where an audible indication is given by the pressure unit 10 the movement of the yoke 40 withdraws the pin 106 from the contact 103 permitting the contact 103 to engage with the contact 104 and complete the circuit for the audible signal 91.

When the depleted tank has been disconnected and a charged tank connected to the header 4, the increased pressure in the header 4 acting 40 upon the diaphragm 26 overcomes the resistance of spring 64, raising the yoke 40 and permitting the latch 60 to be raised by the spring 66. The operator may then restore the piston 52 to the position shown in Figure 3, whereupon the 45 latch 60 will engage in the notch 58 and retain the piston in that position. This movement of the piston resets the indicator 16 to the normal indication and shifts the arm 82 and pin 82' to disengage the pin 82' from the contact 100 and open 50 the circuit of the bell 94. The raising of the diaphragm 26 and the yoke 40 causes the pin 106 to disengage the contact 103 from the contact 104 and opens the circuit of the bell 91.

55

What is claimed is:—

1. A pressure indicator comprising an indicating means, means for operating said indicating means including pressure operated means, means comprising a spring actuated piston for developing fluid pressure for operating said pressure operated means, means for shifting said piston to compress said spring, means retaining said piston in position with the spring compressed and means responsive to the pressure whose condition is to be indicated for releasing said spring actuated piston.

60

2. A pressure indicator comprising an indicating means, pressure operated means, means connecting said pressure operated means and said indicating means, means comprising a spring operated plunger for developing fluid pressure for operating said pressure operated means, a latch for preventing operation of said plunger by said spring to develop fluid pressure to operate said pressure operated means and means responsive 70 to the pressure whose condition is to be indicated for releasing said spring actuated piston.

65

75

to the pressure whose condition is to be indicated for operating said latch.

3. A pressure indicator comprising an indicating means, pressure operated means, means connecting said pressure operated means and said indicating means, means comprising a spring operated plunger for developing fluid pressure for operating said pressure operated means, a latch for preventing operation of said plunger by said spring to develop fluid pressure to operate said pressure operated means and means operative upon the fall to a predetermined degree of the pressure whose condition is to be indicated to release said plunger from said latch.

15 4. A pressure indicator comprising an indicating means, means comprising pressure operated reciprocating means, means connecting said reciprocating means and said indicating means, means comprising a piston for varying the pressure to operate said pressure operated means, means for operating said piston, said operating means comprising a spring biasing the piston to one position, a latch for retaining said piston in position against the action of said spring means for operating said latch to release said piston and means responsive to the pressure whose condition is to be indicated opposing operation of said latch.

5 0 5. A pressure indicator comprising an indicating means, pressure operated means, means connecting said pressure operated means and said indicating means, a cylinder in which said pressure operated means is loosely fitted, means comprising a piston for varying the pressure in said cylinder for operating said pressure operated means, said means comprising a spring biasing the piston to one position, means for operating said piston, a latch for retaining said piston in position against the action of said spring, a spring for operating said latch to release said piston and a diaphragm responsive to the pressure whose conditions is to be indicated opposing operation of said latch.

6. In a pressure indicating apparatus, an indicating means, pressure operated means including a piston, means connecting said piston and said indicating means, means comprising a spring operated piston for effecting pressure changes to operate the piston of said pressure operated means in combination with a manually operated means for positioning said piston with the spring compressed, latching means for said manually operated means in its spring compressing position and means for releasing said manually operated

means from said latching means operable upon a reduction to a predetermined pressure of the pressure whose condition is to be indicated.

7. In a pressure indicating apparatus, an indicating means, pressure operated means including a piston, means connecting said piston and said indicating means, pressure varying means comprising a spring operated piston for varying the pressure to operate the piston of said pressure operated means in combination with a manually operated mechanism for positioning said piston with the spring compressed, a latch for retaining said manually operated mechanism in spring compressing position, a spring for releasing said latch and pressure responsive means opposing operation of said latch by said spring.

8. In a pressure indicating apparatus, an indicator, pressure responsive means for operating said indicator, means including a spring actuated piston for effecting pressure changes to operate said pressure responsive means, in combination with manually operable means for setting said piston in opposition to said spring, a latch for holding said piston in a position with said spring compressed, and trip means for releasing said piston upon a predetermined reduction of the pressure whose condition is to be indicated.

9. In a pressure indicating apparatus, an indicator, pressure responsive means for actuating said indicator, means including a spring biased piston for effecting pressure changes to operate said pressure responsive means, in combination with manual mechanism for setting said piston in a position with said spring compressed, a latch for said manually operated mechanism, a spring release for said latch, and means responsive to the pressure whose condition is to be indicated for opposing movement of said latch by said spring.

10. Pressure indicating apparatus comprising in combination, an indicator, interconnected cylinders each having a piston therein, resilient means tending to advance one of said pistons, manual means for moving said piston in opposition to said resilient means, a latch for holding said piston in position in opposition to said resilient means, tripping means for said latch responsive to changes in the pressure to be indicated, and means connecting said indicator and the other of said pistons, the latter being movable in response to fluid pressure changes caused by movement of said first named piston.

ROBERT G. MINER, JR.

CERTIFICATE OF CORRECTION.

Patent No. 2,050,113.

August 4, 1936.

ROBERT G. MINER, JR.

It is hereby certified that error appears in the printed specification of the above numbered patent requiring correction as follows: Page 3, first column, lines 36-37, claim 5, strike out the words and comma "said means comprising a spring biasing the piston to one position," and insert the same after "piston," in line 38, same claim; and that the said Letters Patent should be read with this correction therein that the same may conform to the record of the case in the Patent Office.

Signed and sealed this 29th day of September, A. D. 1936.

Henry Van Arsdale
